United States Patent Office

Des. 218,590
Patented Sept. 8, 1970

218,590

SEWING CHEST

Albert C. Petitto, Hudson, Mass., assignor to Lerner
Manufacturing, Inc., Melville, N.Y., a corporation of
New York

Filed June 20, 1969, Ser. No. 17,799

Term of patent 14 years

Int. Cl. D6—99

U.S. Cl. D3—19

FIG. 1

FIG. 2

FIG. 3

FIG. 4

FIG. 1 is a top, front and left side perspective view of a sewing chest embodying my new design;

FIG. 2 is a top plan view thereof;

FIG. 3 is a rear elevational view thereof; and
FIG. 4 is a right side elevational view thereof.

I claim:

The ornamental design for a sewing chest, as shown.
